UNITED STATES PATENT OFFICE.

JOSIAH B. HOSTEDLER, OF EGLON, WEST VIRGINIA.

WHIP-SOCKET.

1,087,659.

Specification of Letters Patent. Patented Feb. 17, 1914.

Application filed October 12, 1910. Serial No. 586,696.

To all whom it may concern:

Be it known that I, JOSIAH B. HOSTEDLER, a citizen of the United States, residing at 5 EGLON, in the county of Preston, State of West Virginia, have invented certain new and useful Improvements in Whip-Sockets; and I do hereby declare the following to be a full, clear, and exact description of the invention, such as will enable others skilled in 10 the art to which it appertains to make and use the same.

My invention relates to improvements in whip sockets more particularly to a device of this character in which the whip may be 15 locked in its socket and my object is to provide a construction which will accomplish this result in a simple and efficient manner.

A further object is to provide means whereby the device may be adapted for use 20 with the conventional form of whip without altering in any manner the construction thereof.

A still further object is to provide means for rendering the socket securing parts in 25 accessible when the whip is in place.

It will also be understood that a primary object which governs to some extent every other consideration is to simplify the construction of the device to a point which will 30 reduce its cost within reasonable limits.

With the above and other objects in view this invention consists in the construction combination and arrangement of parts hereinafter described and illustrated in the 35 accompanying drawings which form a part of this application.

In the drawings Figure 1 is an elevation of the socket proper showing also clamps for securing the same to the dash-board of the 40 vehicle, Fig. 2 is an elevation of a locking sleeve shown attached to the shank of a whip, Fig. 3 is a sectional elevation of the device as a whole showing the relations of the various parts, and Fig. 4 is a cross-section taken on the line 4—4 of Fig. 1 and intended to illustrate more particularly the 45 dash board clamps and means of securing the same to the socket.

Referring to the drawings in which similar reference numerals designate corresponding parts throughout the several views, 1 represents the body of the socket which is of 50 conventional form and preferably provided with a bead 2 at the top. Adjacent the 55 lower extremity of the socket is an offset casing 3 which serves as a housing for a bolt

4 and the usual or any preferred form of locking mechanism 5. A key hole 6 is formed in the front face of the casing and in the dividing wall between the casing and 60 socket an aperture 7 serves to permit the passage of the locking bolt 4 when actuated by a key inserted in the hole. As shown the bolt 4 is provided with a cam or curved face with which a spring 8 coacts to retain the 65 bolt in operative position.

9 designates the shank or handle of a whip stock which is of the usual cylindrical form, and in order to adapt this shank to the locking member of the socket a sleeve 70 10 is provided. This sleeve is preferably in the form of a sheet metal cylinder slotted for the greater part of its length, as shown at 11, in order to make it adaptable for whips of sizes varying within reasonable 75 limits. The lower part of the sleeve is formed with a struck-up annular portion 12, the shoulder formed thereby serving as a support for the base of the whip, as shown in Fig. 3. This recess is so positioned with 80 respect to the bottom of the sleeve that when the sleeve rests in the socket the recess will be in operative relation with the locking bolt 4. The sleeve is intended to be permanently attached to the handle of the whip by 85 means of rivets or screws 12' and as said sleeve forms in effect the handle itself, it is preferred that it should be made of aluminum, nickel, or other non-oxidizing metal.

In order to secure the whip socket to the 90 dash of the vehicle which is designated by 13, I provide a pair of return-bent resilient clamping members 14 which are preferably of sheet metal with thickened extremities 95 15 having alining tapped holes therein. These clamps are adapted to pass around the vertical edge of the dash with their center lines in approximately horizontal position. The socket is fastened to these clamps and to the dash by means of screws 100 16 passing through a counter-sunk opening 17 in the back wall of the socket and threaded into the tapped holes of the clamping member.

In order that the head of the screw may 105 be reached by a tool for applying or removing the same, holes 18 are formed in the other wall of the cylinder diametrically opposite the heads of the screws, and it will be seen that a screw driver may be readily introduced through the openings to reach the screw head. It will further be seen how- 110

ever that when the whip is in place in the socket there is no possible method of detaching the socket from the dash short of absolute destruction of some portion of the 5 device.

I am aware that it is old to provide locking whip sockets of this general description but I am not aware of any previous use of the particular form of locking sleeve I have 10 employed nor the method of securing the socket as a whole against theft.

What I claim is:—

15 In combination with a tubular socket, of a locking bolt carried by the socket, a sleeve having a slot formed in one side for a major portion of its length to permit said sleeve

to expand or contract to receive whip butts of various sizes, an annular inwardly directed bead formed in the unslotted portion of the sleeve to provide an outwardly opening 20 groove and an interior shoulder, whereby when a whip butt is engaged in the sleeve, the lower end thereof will rest upon said shoulder, and means passing through the sleeve for permanently securing the same to 25 the whip butts.

In testimony whereof, I affix my signature, in presence of two witnesses.

JOSIAH B. HOSTEDLER.
